UNITED STATES PATENT OFFICE.

ELMER ELSWORTH STILLWELL, OF ORIZABA, MEXICO.

COMBINATION FLUE-EXPANDER AND BEADING-TOOL.

1,115,612.

Specification of Letters Patent.

Patented Nov. 3, 1914.

Application filed March 20, 1914. Serial No. 825,995.

To all whom it may concern:

Be it known that I, ELMER ELSWORTH STILLWELL, a citizen of the United States of America, residing at Orizaba, Republic of Mexico, and State of Vera Cruz, have invented certain new and useful Improvements in Combination Flue-Expanders and Beading-Tools, of which the following is a specification.

10 This invention relates to new and useful improvements in flue expanders and is particularly adapted for use in boiler factories and the like.

15 An object of this invention is to provide a simple and effective device by means of which a boiler flue may be easily and quickly secured in place.

20 Another object of the invention is to provide a tool by means of which the boiler tube may be expanded and beaded in a single operation, thus eliminating the necessity of providing a tool for each operation.

25 Still another object of this invention is the provision of a tool of the above character which is capable of being used with either a steam, air or electric hammer.

30 A further object of the invention is to provide a device which is particularly simple in construction, easily operated and effective in use.

35 With these and other objects in view, the invention consists in the novel combination and arrangement of parts which will be described in detail, in the following specifications and accompanying drawings in which,—

40 Figure 1 is a side view in elevation of a tool constructed in accordance with this invention showing the same as it would appear when in use. Fig. 2 is an edge view of the tool. Fig. 3 is a longitudinal sectional view of the tool, and Fig. 4 is a detail perspective view of one of the tube engaging elements.

45 Referring now to the drawings the numeral 1 designates as an entirety a tool constructed in accordance with this invention, while the numeral 2 designates the boiler sheet, in which the boiler tube 3, which is to be expanded and beaded is adapted to be inserted.

50 The tool 1 comprises the cylindrical outer casing 4, having formed integral therewith a pair of outstanding members 5 and 6, each of which is provided intermediate its ends with the ears 7 and 8. A suitable bolt

receiving aperture is formed in each of said ears and is arranged to align with the corresponding aperture in the opposite ear. Formed intermediate the ears and centrally of the longitudinal axis of the device are the apertures 9 which are arranged to come in direct alignment with each other as shown in the drawings. A centrally located longitudinal bore 10 is formed in the cylindrical outer casing and is arranged to receive the plunger 11 having formed integrally at one end the cylindrical extension 12. Extending through the apertures formed in the ears 7 and 8 are provided the bolts 13 and 14 respectively which are provided with the nuts 15 to hold the same in place.

55 The expanding and beading members which are designated generally by the numeral 16 preferably comprise the substantially triangular body portion 17 having one edge curved at 18. This curved edge 18 is provided near one extremity with the recess 19 the end walls of which are arranged to form the expanding element 20 and the beading element 21 respectively. The adjacent edge of the body portion 17 is provided with the enlargement 22 which is rounded as at 23 to form the cam surface 23 which is arranged to engage the end of the plunger 11 opposite the extension 12 as clearly shown in the drawings. A suitable aperture 24 is formed in the body portion 17 and is arranged to receive either of the bolts 13 or 14 when the device is in use.

60 It will be evident from the foregoing that in use the device is placed in the boiler tube, which is to be secured in place, as illustrated in Fig. 1, and upon inserting the device as far as possible and striking the reduced cylindrical end of the plunger 11, with a hammer of any suitable type, the cam surfaces 23 which rest against the end of the plunger 11 will be forced outwardly which will cause the expanding elements 20 to engage the inner wall of the boiler flue and force the same outwardly. At the same instant the beading elements 21 will engage the outer end of the boiler flue and flange the same outwardly thus firmly securing the tube in the boiler sheet. The flat bottom wall of the recess 19 will engage the inner wall of the flue and thus force the said flue into frictional engagement with the wall of the aperture in the boiler sheet and form a water tight joint.

65 70 75 80 85 90 95 100 105 110 While in the foregoing the preferred em-

bodiment of this invention has been illustrated and set forth, it is to be understood that such changes in the combination and arrangement of parts may be made without departing from the spirit and scope of the invention as claimed.

What is claimed is:—

- 10 In a device of the character described, the combination, with a cylindrical casing having a longitudinal bore, outstanding members formed on the casing, a plunger slidable through the bore, spaced and apertured ears formed on the outstanding members and bolts extending through the apertures in the
15 ears, of expanding elements pivotally held between the ears, said expanding elements

each comprising a substantially triangular body having an outwardly projecting end and a curved edge, and also having a curved recess at the outer end of the curved edge, 20 expanding and beading elements formed by the walls of the recess, and an enlargement formed on the adjacent wall of the body to form a cam for engagement with the end of the plunger.

25 In testimony whereof I affix my signature in presence of two witnesses.

ELMER ELSWORTH STILLWELL.
